FIG. 8

FIG. 9

FIG. 10

FIG. 5

FIG. 6

FIG. 1 is a view in perspective of a knife or similar article showing my new design;

FIG. 2 is a side view in elevation thereof;

FIG. 3 is a top plan view thereof;

FIG. 4 is a bottom plan view thereof;

FIG. 5 is an enlarged cross-sectional view taken on line 5-5 of FIGS. 2 and 8;

FIG. 6 is an enlarged cross-sectional view taken on line 6-6 of FIGS. 2 and 8;

FIG. 7 is a view in perspective of a boning knife or similar article on the same scale as FIG. 1 incorporating a variant of the same ornamental design concept shown in FIGS. 1 through 6;

FIG. 8 is a side view in elevation thereof;

FIG. 9 is a top plan view thereof, and

FIG. 10 is a bottom plan view thereof.

The essential features of my design reside in the showings of the handles, which are integral with the respective blades. The design is generally characterized by integrally formed handles having variably convex sections adjacent the free end thereof and variably flattened sides at the end adjacent the blade, all as shown.

I claim:

The ornamental design for a knife or similar article, as shown and described.
